US00D724060S

(12) **United States Design Patent**
Ahn et al.

(10) **Patent No.:** **US D724,060 S**
(45) **Date of Patent:** **** Mar. 10, 2015**

(54) **REMOTE CONTROLLER**

- (71) Applicant: **Samsung Electronics Co., Ltd.**, Suwon-si, Gyeonggi-do (KR)
- (72) Inventors: **Hyo-In Ahn**, Seoul (KR); **Eun-Kyung Yoo**, Seoul (KR); **Ji-Su Jung**, Yongin-si (KR); **Dong-Goo Kang**, Seoul (KR); **Say Jang**, Yonginsi (KR)

(73) Assignee: **Samsung Electronics Co., Ltd.** (KR)

(**) Term: **14 Years**

(21) Appl. No.: **29/486,785**

(22) Filed: **Apr. 2, 2014**

(30) **Foreign Application Priority Data**

- Oct. 24, 2013 (KR) 30-2013-0053548
- (51) **LOC (10) Cl.** **14-03**
- (52) **U.S. Cl.**
USPC **D14/218**
- (58) **Field of Classification Search**
USPC ..... 116/106; 174/84 R; 200/5 R; 340/287, 340/396.1, 691.7, 693.11; 446/106; D10/106.5, 49, 50, 65, 70; D13/171, D13/173, 174, 168; D14/137, 218, 240, D14/242, 245, 420; D16/203; D22/122; D28/82, 91; D9/420, 504; D7/401

(57) **CLAIM**

We claim, the ornamental design for a remote controller, as shown and described.

DESCRIPTION

FIG. 1 is a perspective view of a remote controller, showing our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines are for environmental purpose only and form no part of the claimed design.

1 Claim, 4 Drawing Sheets
